UNITED STATES PATENT OFFICE.

HENRY CEEPO, OF CLEVELAND, OHIO.

CASING HOOK.

Application filed June 15, 1925. Serial No. 37,220.

The objects of the invention are to provide an improvement in carpenters' tools which is capable of being employed for several uses and particularly for cutting and measuring siding and base timbers and for fitting door and windows casings, and for other purposes incidental to carpenters' work.

The character and details of the construction are illustrated in the accompanying drawings, hereinafter more fully described and specifically pointed out in the claims.

In the accompanying drawings Fig. 1 is a plan of the device; Fig. 2 is a side elevation thereof; Fig. 3 is a bottom plan thereof.

The invention comprises two elongated members such as bars, A and B, having lateral offsets C and D intermediate of their respective ends. These offsets are preferably at right angles to the elongated members and the parts accurately fit and overlap each other.

One member, A, serves as a base for the implement and the other, B, is laterally movable toward and from the same upon guide pins E, E, and is operated by means of the nut F mounted upon a screw F' parallel with the pins E, E, and enclosed in the recess or fork G in one extremity of the upper member, the pins being secured in the lower member.

Also the under surface of the lower member is offset at H and the shoulder thus formed is beveled at 45° or other degree if desired. The upper surface of the upper member is graduated at I to form a carpenter's scale.

Also an awl or scratch pin or pencil J can be inserted in an opening in one end of the lower member which is made heavier than the other end to receive the pins E, E.

This end of the upper member is also shorter than the adjacent end of the lower member, and is thickened to contain the fork G.

The advantages of the device are numerous. The offset shoulder upon the upper member permits it to be employed as a square. The beveled shoulder upon the bottom permits it to be used to form mitre joints.

The device may be used as a siding hook or as a casing hook and the sides are minutely adjustable towards and from each other. Also the scale assists in positioning the implement before the casing or siding is severed, and permits the workman to check up on his work, and prevents mistakes from being made.

It is also convenient to have a marking ac-

cessory within the tool so that it may be instantly accessible to the workman and will not be lost where needed.

The position of the bevelled shoulder is 60 convenient for mitre work of all sorts and the right angles provide means for properly cutting wood neatly at right angles in a manner similar to the use of squares.

Having described the invention what I 65 claim as new and desire to secure by Letters Patent is:

1. In a device of the class described, upper and lower elongated members having lateral offsets intermediate of their ends, said offsets 70 being at right angles to said members and adapted to fit accurately and overlap each other, one member serving as a base for the device, the other member being laterally movable toward and from the same, the upper member having a forked recess, guide pins connecting said members, a screw parallel with said pins for operating said upper member, a nut therefor inclosed in the forked recess in one extremity of the upper member, 80 said lower member being also provided with an offset on its lower side, the upper surface of the upper member being graduated and also provided with an offset permitting the same to be used as a square. 85

2. In a device of the class described, upper and lower elongated members having lateral offsets intermediate their ends, the upper member having a bifurcation in one extremity, guide pins connecting said members, a 90 nut parallel with said pins, a nut thereon for operating said upper member, said nut being disposed in the bifurcated end of the upper member, said lower member being also provided with an offset on its lower side, the upper surface of the upper member having graduations thereon and also having an offset permitting the device to be used as a square. 95

3. In a device of the class described, upper and lower elongated members having lateral offsets intermediate their ends, guide pins connecting said members, means for moving said upper and lower members toward and from each other, said lower member having a 45° offset on its lower side, the upper surface of the upper member being provided with graduations and also with an offset permitting the same to be used as a square. 105

In testimony whereof, I hereunto set my 110 hand this 10th day of June, 1925.

HENRY CEEPO.
